UNITED STATES PATENT OFFICE.

JAMES H. BOYE, OF CHICAGO, ILLINOIS.

CURTAIN FIXTURE.

Application filed November 10, 1921. Serial No. 514,161.

To all whom it may concern:

Be it known that I, JAMES H. BOYE, a citizen of the United States, residing at Chicago, in the county of Cook and State of Illinois, have invented certain new and useful Improvements in Curtain Fixtures, of which the following is a specification.

This invention relates to improvements in fixtures or hangers designed to support window curtains and drapes, or portières and the same is in the nature of an improvement upon the curtain hanger disclosed in Letters Patent No. 1,288,493, granted to me December 24, 1918.

My present invention employs the same tubular expansible curtain or drape rod, preferably of corrugated form that is disclosed in the aforesaid patent; and my present improvements relate chiefly to improved means for supporting and detachably locking the ends of the rod to the end supporting brackets.

My invention, its novel structural features, and the advantages inhering therein will be readily understood by persons familiar with the art from the following detailed description, taken in connection with the accompanying drawings, wherein I have illustrated practical embodiments of the invention adapted for use both as a hanger for window curtains and as a hanger for portières, and in which—

Fig. 1 is a front elevation of my improved curtain hanger, showing the same applied to a window frame for carrying window curtains;

Fig. 2 is an enlarged longitudinal section through a portion of the rod and its supporting and locking bracket;

Fig. 3 is a cross-section on the line 3—3 of Fig. 2;

Fig. 4 is a plan view of a sheet-metal blank from which the body and arm of the supporting bracket are formed;

Fig. 5 is a longitudinal section through the bracket showing the snap hook in end elevation;

Fig. 6 is a longitudinal section similar to Fig. 2, showing a form of supporting bracket adapted for application to the inner side of a door frame, where the device is to be used as a portière hanger; and

Fig. 7 is a cross-section on the line 7—7 of Fig. 6.

Referring first to the form of the invention illustrated in Figs. 1 to 5 inclusive; 19 designates the intermediate section, and 11 the end sections of a hollow corrugated sheet-metal telescoping curtain rod, for a fuller description of which reference may be had to my former patent above-identified. A novel feature of the said rod, however, which constitutes an element of my present invention consists of an annular lip or flange on the outer end of each end section of the rod. As herein shown this lip or flange takes the form of an annular sheet-metal washer 12 that is secured to the rod by bending or crimping the end of the latter over the periphery of the rod, as shown at 13 in Fig. 2, and punching out and bending down inwardly extending tongues 14 that bear against the inner surface of the washer. This flat sheet metal washer is snugly fitted within the end of the rod and constitutes in effect a transverse end wall of the latter that stiffens the rod transversely and maintains its round form; the central aperture 15 of the washer co-operating with a hook on the bracket hereinafter described to separably interlock the rod with the bracket.

Referring next to the supporting bracket, this is assembled from a pair of sheet-metal members. Fig. 4 illustrates a sheet-metal blank that is bent and crimped to provide the body, arm and attaching base or flange of the bracket. This blank comprises a central rectangular portion A and a pair of wings B continuous with the ends of the central portion A. The central portion A is bent in circular form, providing a circular socket 16 of a size to slidably fit the outer end portion of the end section 11 of the rod. The wings B which are transversely concaved, are brought into meeting relation, and the longitudinal margins of one wing are folded over the corresponding margins of the other, as shown at 17 in Figs. 3 and 5, thereby providing a strong, rigid hollow bracket arm 18. The outer ends of the wings B of the blank are bent outwardly substantially at right angles to form an attaching base or flange 19 through which are punched holes 20 to receive fastening screws.

To the outer end of the socket member 16 is applied a sheet-metal cap 21, conveniently secured in place by bending or folding the marginal edge 22 thereof over the

socket member 16 behind an external annular rib 23 formed on said socket member 16.

5 The device as thus far described is complete as a curtain hanger or support; but, where the extensible or telescoping rod is employed, it is preferable to provide means for detachably locking the ends of the rod in and to their supporting brackets to prevent accidental dislocation of one or both ends of the rod. My invention, in its most complete form, includes a simple device for thus locking the ends of the rod in their supporting brackets. To the inner side of 10 the cap 21 is secured by a rivet 24 an inwardly extending spring hook or catch 25. This hook or catch is shown bent to form a cam incline 26 terminating in a hump or protuberance 27, with a rearward extension 15 28 from the latter which passes through a central hole 29 in the cap 21. As the end 20 of the rod section 11 is passed into the socket 16, the inner edge of the lip or flange 12 rides up the cam incline 26, depressing 25 the upper limb of the catch until it passes the hump 27, whereupon the latter snaps upwardly behind and into locking relation with the lip or flange. With one end of the 30 rod thus entered and yieldably locked in one bracket, the rod may be pulled out or extended and its other end similarly entered into and yieldably locked to the other bracket. One valuable feature of the lip or flange 12 as an element of the locking 35 device resides in the fact that it functions with the snap hook in any relative circumferential position of engagement of the rod and socket, thereby making it unnecessary to turn the rod to any particular position 40 before passing it into the socket in order to effect the locking engagement of the two. The rod is easily withdrawn from the socket by simply depressing the hook extension 28 by the thumb or finger, thereby lowering 45 the hump 27 to or below the edge of the hole 15.

Figs. 6 and 7 illustrate a rod supporting member embodying in part the structural principle already described, and adapted to serve as a simple support and lock for a portière rod mounted between the inner opposed sides of either a window or door frame. In this form of the invention, the rod may be either a single piece rod or an extensible telescoping rod, but the ends thereof are equipped with the same flat sheet metal washer 12. The supporting bracket essentially comprises merely a flat plate 30 formed with holes 31 for attaching screws, and a central inwardly and upwardly extending tongue or hook 32, conveniently cut and bent from the plate 30. This bracket being applied to the window or door frame in the manner indicated in Fig. 6, the rod is applied and removably locked

thereto by simply entering the central hole 15 over the hook 32 and letting the lip or flange 12 drop into engagement therewith. The rod is disengaged by the reverse of this operation. To give to the bracket a neater and more finished appearance, the lower portion thereof is preferably provided with an integral semicircular lip or flange 33 that overlaps the lower half of the end portion of the rod. Incidentally, this lip or flange 33 may serve in part as a support and steadyng device for the rod, but it is not essential for such purpose. When using this form of supporting bracket it is, of course, necessary to lift the end of the rod slightly before it can be disengaged from the rigid hook 32, which lifting movement is not required in the structure illustrated in Figs. 1 to 5 inclusive. This form of the invention, however, like the first described form permits what may be termed a universal application of the rod to the bracket, in the sense that it is not necessary to particularly position the rod angularly on its axis before engaging it with the bracket. 90

It is believed that the structure, mode of use, and advantages of the invention will be readily understood and appreciated from the foregoing without further detail description. Obviously, the structure may be variously modified in respect of details without altering its substantial character or sacrificing the advantages inherent therein. Hence, I reserve all such variations and modifications as fall within the spirit and purview of the appended claims. 95 100

I claim:

1. In a curtain fixture, the combination of a hollow sheet metal curtain rod, centrally apertured flat sheet metal washers fitted within the ends of said rod and constituting transverse end walls of the latter, said rod having integral inwardly bent portions gripping the periphery of said washers to secure the latter in place, and supporting brackets for said rod each provided with a hook adapted to pass through and interlockingly engage with the washer in the adjacent end of the rod.

2. In a curtain fixture, the combination of a round hollow curtain rod having at each end an inwardly extending annular lip, supporting brackets for said rod each having a round socket member adapted to receive and encircle an end of said rod, and a snap hook in each of said socket members automatically engaging with the annular lip of said rod under an inward sliding movement of the latter, said snap hook having a free end portion extending outside said socket member by manipulation of which said hook may be disengaged from said lip. 115
120
125

3. In a curtain fixture, the combination of a round hollow curtain rod having at each end an inwardly extending annular lip, sup-

porting brackets for said rod each having a socket member adapted to receive an end of said rod, said socket member comprising a circular body and an apertured cap on the outer end of said body, and a snap hook in each of said socket members automatically engaging with the annular lip of said rod under an inward movement of the latter, said snap hook having a free end extension passed through the aperture of said cap by manipulation of which said hook may be disengaged from said lip. 10

JAMES H. BOYE.
